UNITED STATES PATENT OFFICE.

LEWIS SMITH, OF BUFFALO, NEW YORK.

COMPENSATION-BEARING.

Specification of Letters Patent No. 12,732, dated April 17, 1855.

To all whom it may concern:

Be it known that I, LEWIS SMITH, of Buffalo, in the county of Erie and State of New York, have invented a new and Improved 5 Mode of Constructing Bearings for Machinery, which is described and set forth in the following specification and accompanying drawings with sufficient clearness to enable others of competent skill to make and 10 use my invention.

It is a well known fact that the metal of which gibs and bearing boxes for journals are usually composed expands much more by heat than the iron crossheads or pillow- 15 blocks which confine them in position and consequently that a bearing of this kind keyed up to its proper tightness when cold becomes too tight as soon as the box or gib becomes worn from running which increases 20 the tightness and causes more friction and that in turn, a greater heat and tightness till the bearing surfaces are in many cases very much damaged or destroyed.

My invention consists in methods of construction which causes the heat of the bearing to relieve it of undue tightness by the combination of metals of different expansibility as herein set forth.

In the accompanying drawings Figure 1 30 is a sectional perspective view of a part of a crosshead with a pair of gibs embodying the principles of my invention. Fig. 2 is a vertical longitudinal section of one of the gibs. Fig. 3, is a light transverse section of 35 the same gib. Fig. 4 is a vertical projection of a journal box embodying the same principle of construction, the plane of projection being transverse to the axis of the journal. Fig. 5 is also a vertical projection 40 of the same journal box, the plane of projection in this figure being parallel to the axis of the journal. Fig. 6 is a vertical sectional projection of a bearing suitable for a mandrel of a turning lathe or machinery 45 of a similar nature.

A A A is part of a cross head of an engine.
B is part of a slide.

C is a gib made according to my improved plan. Its construction is more fully shown 50 in Figs. 2 and 3. It is made of the composition that brass bearings are generally made of and is chambered in the back side to admit two pieces of iron D, D, which form a toggle joint, the outer ends seating 55 against the ends of the chamber. In Fig. 2 the gib is shown as being cut in two imme-

diate forward of the pieces D, D, and in Fig. 3 as being cut at the joint between them. A flat piece of metal E rests upon the pieces D, D, against which piece E the set screw F 60 is screwed down to adjust the gib to the slide; the upper jaw of the crosshead being represented as cut through at the center of this set screw so as to give a better view of the gib and its appendages. A recess is 65 cut and fitted in the jaw of the cross head to receive the parts D, D, and keep them in place.

It will be seen by the foregoing description and an examination of the drawings 70 that if the brass should bear too heavily on the slide the heat produced by undue friction would instead of tightening it relieve it from pressure as the brass of which the gib is made would expand more than 75 the iron pieces D, D, and thus allow the toggle joint which those pieces form to straighten and the gib to move away from the slide. Figs. 4 and 5 show the same principle of construction applied to journal 80 boxes.

H is one half of a journal box.

I is a piece of iron or steel which performs the same duty in connection with the box that the pieces D perform in connection with 85 the gib; the cap or strap (as the case may be) which holds the piece H in its place resting upon the piece I instead of the box, the iron, as will be seen, rising above the brass for that purpose, in which case the 90 expansion of the brass will allow the crown of it to retire toward the piece I. Fig. 6 shows a method of applying this principle to relieving the bearings at the ends of lathe mandrels, and similar journals. 95

J is a lathe mandrel or journal of similar description. It has a conical hole in the end to receive the center K. This center K is split by a thin slot at the end which enters the spindle or mandrel as will be seen by 100 examining the drawings, which opening will allow the parts to spring together if hard pressed. The end of this center as will be seen in the drawing has less taper than the hole in the mandrel, so that pressing the 105 shaft against this center with any considerable force will press the shaft J against the collar O, to which position it may be adjusted to run. If it should be too tightly adjusted, the friction will be likely to heat 110 the collar O, which being thus caused to expand is by that means allowed to slide

back upon the center pin K for the purpose of relieving it from pressure; the shoulder of the collar, which bears against the shoulder on the center pin K, being tapered or cone shaped as shown in the drawing. The center pin K is hollow to contain oil which is introduced through a hole closed by a cork N.

L is a bracket or other fixture into which the center pin K is fastened by the set screw M. The ring O is also a means of retaining the oil in the center pin K, and excluding the atmosphere from it.

I claim—

Relieving bearings of machinery from un- 15
due pressure and consequent friction by
means of the different expansion of two or
more different metals, the parts being con-
structed, combined, and operating substan-
tially as herein set forth or in any other 20
manner substantially the same.

LEWIS SMITH.
